E. G. CAMELINAT.

LAMP BRACKET.

APPLICATION FILED DEC. 16, 1919.

Patented Aug. 2, 1921.

UNITED STATES PATENT OFFICE.

EUGENE GEORGE CAMELINAT, OF BIRMINGHAM, ENGLAND.

LAMP-BRACKET.

1,386,453.

Specification of Letters Patent.

Patented Aug. 2, 1921.

Application filed December 16, 1919. Serial No. 345,420.

To all whom it may concern:

Be it known that I, EUGENE GEORGE CAMELINAT, citizen of France, residing at 35 Tenby street, Birmingham, England, have 5 invented certain new and useful Improvements in Lamp-Brackets, of which the following is a specification.

This invention relates to lamp brackets or supports for use on motor-cars and other 10 vehicles, motor-cycles and the like, said brackets or supports being of that type which allows of angular adjustment of the lamp both in a vertical and in a horizontal plane.

15 The object of the present invention is to provide means for giving a fine angular adjustment of the lamp in both the said planes, while at the same time giving a secure lock.

According to the invention, the lamp is 20 adapted to be adjusted in a vertical or horizontal plane by means of worm gearing. Preferably the bracket or support comprises a lower fixed vertical socket, a stem or intermediate member rotatably mounted within 25 the socket and adapted to be adjusted therein, in a horizontal plane, by worm gearing, and an upper part carried by the lamp body, jointed to the intermediate member and adapted to be angularly adjusted to give 30 adjustment of the lamp in a vertical plane by means of worm gearing.

Figure 1 of the accompanying drawings represents a side view of a lamp bracket or support constructed in accordance with this 35 invention, the worm gearing for admitting of the lamp being adjusted in vertical and horizontal planes being represented by dotted lines.

Fig. 2 is a front view of same.

40 Fig. 3 shows a horizontal section on the line α , Fig. 1.

Fig. 4 is a longitudinal section through the bracket, the upper portion of the bracket, carried by the lamp body, being shown in an 45 adjusted position.

The same reference numerals indicate corresponding parts in each of the figures.

Referring to the drawings, the lamp body 1 is supported by a depending lug or tongue 2 which engages between the vertical jaws or cheeks of a fork 3 carried at the summit of a stem or pillar 4 having its lower end mounted in a socket 11 on the vehicle. A screw-pin or bolt 5 fitted with a clamping 55 nut 6 and spring washer is passed transversely through the fork 3 and tongue 2 so

as to form a knuckle joint. The tongue 2 is preferably of circular form, and its periphery is provided with worm teeth 7 engaged by a worm 8 on a rotatable spindle 9 mounted in the fork 3. The spindle is inserted into a transverse hole or housing in the body of the said fork 3, its inner end 10 being of reduced diameter and being supported in a bearing or recess at the inner end 60 of the housing. The worm 8 is formed on the intermediate portion of the spindle 9, the outer end being of smaller diameter than the worm and being supported within a removable bush 12 screwed into the outer end 65 of the housing so as to engage the end of the worm 8 and thus prevent back-lash and take the end thrust. The outer end of the bush is provided with a hexagonal head or flange 13, and the spindle 9 extends beyond this flange, 70 being provided with a knob or head 14 for rotation by hand, or formed of square section so that it can be readily rotated by a key or spanner, thus causing the rotation of the worm 8 and the adjustment of the 80 lamp. The latter may be fixed in its adjusted position by tightening up the nut 6 on the pivot of the knuckle joint.

The stem 4 is rotatable within the fixed socket 11 for adjustment of the lamp in a 85 horizontal plane, this adjustment being effected by worm gearing comprising a rotatable worm 15 rotatably mounted within a housing or enlargement of a collar 16 fixed upon the summit of the socket 11 and engaging, through an aperture in the socket, with worm teeth 17 formed on the exterior of the stem 4. A shoulder 18 on the latter rests upon the top of the collar 16 and the worm 15 has a reduced end 19 supported in a bearing or recess at the inner end of the housing. The worm 15 is formed on the intermediate 90 portion of the spindle 20, the outer end being of smaller diameter and being supported within a removable bush 21 screwed into the 100 outer end of the housing so as to engage the end of the worm. The outer end of the bush has a hexagonal flange 22 and the spindle extends beyond this flange and has a knob or head 23 for rotation.

Having fully described my invention, what I desire to claim and secure by Letters Patent is:—

1. A lamp bracket for use on motor vehicles comprising two angularly adjustable 110 members, one member provided with a housing having one end open, the other member

having worm teeth, a worm within the housing of the first-named member and engaging the worm teeth of the other member, and a screw plug closing the open end of said housing and serving as a bearing for one end of the worm.

2. Lamp bracket for use on vehicles, comprising a lower fixed vertical socket member; an intermediate member rotatably mounted in said socket and having a pair of lugs and a housing at its upper end; worm gearing for adjusting said intermediate member in a horizontal plane; a toothed lamp-supporting lug hinged between the lugs of the intermediate member; and a worm in said housing engaging the teeth on the lamp-supporting lug.

3. A lamp bracket for vehicles, comprising a lower fixed member having a socket and a housing at its upper end, an intermediate

member having its lower end provided with worm teeth and mounted in said socket, said intermediate member having a pair of lugs at its upper end and a housing adjacent said lugs; a worm within the housing of the lower member engaging the teeth on the intermediate member; a toothed lamp-supporting lug mounted between the lugs at the upper end of the intermediate member; and a worm in the housing of the intermediate member engaging the teeth on the lamp-supporting lug.

In witness whereof I have hereunto set my hand in the presence of two subscribing witnesses.

EUGENE GEORGE CAMELINAT.
